(57) **CLAIM**

The ornamental design for a digital camera display screen with transitional graphical user interface, as shown and described.

DESCRIPTION

FIG. 1 is a perspective view of the digital camera, showing the new design;

FIG. 2 is a front view thereof;

FIG. 3 is a rear view thereof;

FIG. 4 is a top view thereof;

FIG. 5 is a left view thereof;

FIG. 6 is an enlarged view of a display portion, showing a first image of the display screen, shown separately for clarity;

FIG. 7 is an enlarged view of the display portion, showing a second image of the display screen, shown separately for clarity;

FIG. 8 is an enlarged view of the display portion, showing a third image of the display screen, shown separately for clarity;

FIG. 9 is an enlarged view of the display portion, showing a fourth image of the display screen, shown separately for clarity;

FIG. 10 is an enlarged view of the display portion shown separately for clarity, showing the first image of the design in a differing broken-line context; and,

FIG. 11 is an enlarged view of the display portion shown separately for clarity, showing the fourth image of the design in a differing broken-line context.

The short-dashed broken lines illustrate the perimeter of a display screen and form no part of the claimed design. The long-dashed broken lines outside this perimeter show a digital camera as the environment of the claimed design and form no part thereof. The long-dashed broken lines within this perimeter illustrate portions of the graphical user interface which form no part of the claimed design.

The appearance of the transitional image sequentially transitions between the images shown in FIGS. 6-9. The process or period in which one image transitions to another image forms no part of the claimed design.

1 Claim, 11 Drawing Sheets
